UNITED STATES PATENT OFFICE.

ARTHUR R. SELDEN, OF ROCHESTER, NEW YORK.

TONGS.

1,250,365.

Specification of Letters Patent. Patented Dec. 18, 1917.

Application filed March 3, 1917. Serial No. 152,254.

To all whom it may concern:

Be it known that I, ARTHUR R. SELDEN, a citizen of the United States, and resident of Rochester, in the county of Monroe, and 5 State of New York, have invented certain new and useful Improvements in Tongs, of which the following is a specification.

The present invention relates to tongs, and an object thereof is to provide a construction

10 which will enable the tongs to be made into ornamental form from sheet metal. Another object of the invention is to provide tongs in which a small movement of the operating handles or levers will make a maximum 15 movement of the jaws of the tongs. Still another object of the invention is to provide a construction in which the handles of the tongs will have their forward ends so arranged as to act as a stop for holding the 20 material away from the pivot of the jaws.

To these and other ends, the invention consists of certain parts and combinations of parts all of which will be hereinafter described, the novel features being pointed out 25 in the appended claims.

In the drawings:—

Figure 1 is a view, in side elevation, of tongs constructed in accordance with this invention, showing the tongs in open position;

Fig. 2 is a view similar to Fig. 1, showing the tongs in closed position;

Fig. 3 is a view of one jaw of the tongs;

Fig. 4 is an enlarged section on the line 30 4—4, Fig. 1;

Fig. 5 is an enlarged section on the line 5—5, Fig. 1; and

Fig. 6 is a view of the handle end of the tongs, partly in section.

40 Referring more particularly to the drawings, 1 and 2 indicate the jaws of the tongs. These jaws are preferably formed from sheet metal and stamped into cup form. Each jaw is preferably provided with a pair of ears 3 and 4 which are connected to the ears of the other jaw by a pivot pin 5, the ear 4 being deflected at 6 so that the distance between the ears is the same on the two jaws, and at the same time the jaws are permitted 50 to operate in the same plane.

For operating the jaws 1 and 2, hand levers 7 and 8 are provided, preferably also bent from sheet metal into channel form, and having their forward ends provided 55 with ears 9 and 10, the ears 9 being deflect- ed at 11 so that the distance between the two

ears on the two levers is the same, thus permitting the levers to operate in the same plane about a common pivot pin 12. The hand levers 8 are projected between the ears 3 and 4 of the jaws 1 and 2, so that the pivot 12 of the hand levers 7 and 8 lies in advance of the pivot 5 of the jaws 1 and 2. Each hand lever is pivoted to one of the jaws, the hand lever 7 being pivoted to the jaw 1 at 13, and the hand lever 8 being pivoted to the jaw 2 at 14, these pivots being situated between the pivots 5 and 12. By this arrangement a small movement in the levers 7 and 8 communicates a larger movement to the jaws 1 and 2, thus permitting the jaws to be open to a maximum distance. To the end of forming large grasp surfaces of the levers 7 and 8, each of said levers is enlarged at 18 and also curved, the extreme end 75 of the enlarged portion being bent inwardly at 19 to form a stop for co-operating with a like portion on the other lever, limiting the closed movement of the levers. A latch 20 may be pivoted at 21 to one of the hand 80 levers and have a double nose 22, which may engage with either side of a headed projection 23 on the other hand lever.

With a view of maintaining the jaws normally open, a spring is employed, preferably 85 coiled at 15 about the pivot pin 5, and having arms 16 extending rearwardly and engaging within the channels of the levers 7 and 8.

Tongs constructed in accordance with this 90 invention permit the formation of an ornamental construction from sheet metal. The parts are so formed as to give durability in use, while at the same time a construction is secured in which the jaws have a maximum 95 opening movement for a minimum movement of the operating levers without the employment of a complicated lever action. The forward ends of the hand levers 7 and 8 act as a stop to prevent any articles becoming lodged between the jaws at their pivots. 100

What I claim as my invention and desire to secure by Letters Patent is:

1. Tongs comprising a pair of pivotally connected jaws, and handle levers pivoted 105 on a common pivot at their forward ends and pivoted to the jaws between the common handle pivot and the jaw pivot, the common handle pivot being nearer the outer ends of the jaws than the common jaw pivot. 110

2. Tongs comprising a pair of jaws pivot- ed on a common axis, handle levers pivoted

together at their forward ends and pivoted to the jaws in rear of the handle axis and in front of the common jaw pivot, and a spring surrounding the pivot of the jaws and having two arms acting against the handle levers.

3. Tongs comprising a pair of cupped jaws each of which has a pair of ears pivoted to the ears of the other jaw, one ear of each jaw being deflected so that the distance between the ears is the same on the two jaws

and the jaws operate in the same plane, and a pair of hand levers having channelled forward portions each provided with a pair of ears, the ears of one hand lever being pivoted to the ears of the other hand lever, and levers extending between the ears of the jaws with the pivot of the levers in advance of the pivot of the jaws, each lever being pivoted to one of the jaws between the pivot of the levers and the pivot of the jaws.
